UNITED STATES PATENT OFFICE.

JOHN A. WILLNERS, OF PHILADELPHIA, PENNSYLVANIA.

FUEL BURNER.

Application filed April 18, 1923. Serial No. 632,852.

My invention relates to fuel spraying and burning. The object is to provide improved method and means for delivering a fuel spray or/and vapor, mixed with air to a suitable place or region for combustion. The invention is especially adapted to operate upon heavy fuel oil or other liquid carbon.

The invention comprises means for forcing the fuel through minute orifices under pressure into an enclosed chamber in order to break up to a certain extent, the mass or body thereof, then forcing the same, under pressure, through comparatively small channels extending from near the outer circumference of the chamber toward a centrally disposed circular space or recess: said channels delivering tangentially to said recess in order to give a whirling motion or direction to the stream or streams of fuel emerging from said channels. The whirling streams are delivered from said recess, through an outwardly flaring port, registering approximately with said recess, into an enlarged compartment of greater dimension than said port, in order that the whirling streams shall expand, to further break up the particles of fuel. The compartment then contracts or tapers into a cone-shaped formation, to a vent in the apex of the cone. This tends to subject the fuel to compression again, after said temporary expansion, further to disturb or break up its constituent particles. The vent at said apex causes the sudden release of the fuel subjected to said pressure, so that the same shall be thoroughly sprayed and partly atomized or vaporized as it issues from said nozzle vent into the atmosphere.

The invention also comprises method and means for producing an air current or stream enveloping and impinging the fuel as it issues from the nozzle vent, and improved method and means for preventing drip of the fuel from said nozzle vent. The invention also comprises improved method and means for forming and assembling the various elements for effecting the objects required.

Referring to the drawings, which illustrate merely by way of example suitable means for effecting my invention:

Fig. 1 is a central longitudinal section.

Fig. 2 is a detail in perspective of the perforated cylinder.

Fig. 3 is a view in perspective of the flaring port element.

Fig. 4 is a section on line 4—4 of Fig. 3.

Fig. 5 is a perspective view of the channelled element.

Fig. 6 is a front elevation of same.

Fig. 7 is a rear elevation of same.

Similar numerals refer to similar parts throughout the several views.

The chambered body 8 is cylindrical in formation having one end open and internally threaded as at 9, the other end 10 is cone shaped with a vent 11 at the apex of the cone. The outer surface of the cone-shaped nozzle is provided with a fin or flange 12, for the purpose to be explained. The open end of body 8 is closed by the plug formation 13 threaded therein, and connected to or having the pipe 14, which is adapted to be connected to a source of fuel supply under pressure. Within the body 8 are provided the elements 15, 16 and 17; 15 being in the form of a disc with the flaring port 18 flaring toward the spray vent 11. This element or disc 15 fits snugly within the cylinder of body 8 and engages the wall at the base of the cone formation 10. Element 16 has a flange like formation 19 which fits snugly the inner wall of the cylinder 8 with its flat face against the rear face of disc 15. Integral with this flange is an extension 20 of lesser diameter extending concentrically with the flange. In the face of the flanged formation, which rests against element 15, there is provided a centrally disposed circular recess or depression 21, and four channels or slots 22, evenly spaced apart, extending entirely through the flange from its periphery, tangentially to the central recess 21, as clearly shown in Fig. 5. The elements 15 and 16 serve as a partition to divide the interior of the body 8 into the cylindrical compartment 23 and the conical compartment 24.

It will be noted that channels 22 correspond in depth to the thickness of flange 19 which is also the depth of recess 21. Since the extension 20 is of less diameter than flange 19, it will be obvious that the portion of the channels which project beyond the

circumference of extension 20 will form ports or passages from the compartment 23 to said channel 22 and the recess 21. The flaring port 18 delivers from the channels 22 and recess 21 to the compartment 24.

The element 17 is a perforated cylinder preferably of sheet metal. One end of this cylinder fits over a reduced portion 25 of an inwardly projecting part or nozzle 26 from plug 13; the other end abuts against element 16. This cylinder is held in position against element 16 by the pressure of plug 13, threaded into body 8. In fact all the elements 15, 16 and 17 are held in operative position by the pressure of member 13.

The interior or bore 27 of plug 13 delivers to the interior of cylinder 17 and the fuel emerges therefrom through the perforations 28.

20 The body 8 is adapted to be supported in the opening 29 of a combustion chamber or pan. This opening 29 is considerably larger than body 8 and communicates with a pipe or conductor 30, surrounding body 8 25 and leading from a source of air supply under pressure.

It will be noted that opening 29 has a bevelled margin so that the inlet side, toward pipe 30, is larger than the discharge side; this tends to compress the air stream and direct it toward the fuel stream issuing from vent 11 and toward the fin or flange portion 12. The purpose of this is to bring the air and fuel into closer contact and to cause a partial mixing as the air passes through port 29. The air stream or current sweeping, in converging lines, over the end of nozzle 10 and the flange portion 12, tends to sweep with it any fuel which might otherwise tend to drip or dribble from vent 11, down the walls of the nozzle to the fin 12.

In operation, the fuel is delivered, under pressure, by a suitable pump or similar device, not shown, through passage 27 to the interior of the perforated cylinder 17, and emerges through the perforations of the cylinder into the surrounding cylindrical compartment or chamber 23. In the case of heavy oil or similar fluid fuel, its passage, 50 in fine streams through the said perforations, tends to break up the mass of fuel in small particles. This fuel then passes through the tangentially arranged channels 22 to the central depression or recess 21, and 55 forms therein a whirling mass which passes in whirling streams through the flaring port 18, into the conical compartment 24. The end of compartment 24, adjacent port 18, is larger in cross-section than said port, which 60 permits expansion of the whirling mass of fuel delivered through port 18. The part of the compartment 24, which is remote from port 18, is contracted or cone-shaped, with 65 the vent 11 at its apex. This causes a compression of the fuel before its release through

the vent, which results in an effective spraying of the fuel issuing through said vent.

The current of air under pressure, passing through the pipe or conduit 30 is delivered to the port or opening 29, which is contracted or bevelled toward its delivery side. This tends to sweep the air currents toward the nozzle vent 11, so that the same will more effectually impinge the fuel spray issuing therefrom, and cause a mixing of the air and fuel emerging through port 29, for combustion.

What I claim is:—

1. In a fuel burning device, the combination of a chambered body having an outwardly projecting conical end and a discharge vent, at the apex thereof, means, comprising a flanged element, dividing the interior of the chambered body into two compartments, said flanged element provided, in its face towards the discharge vent, with a centrally disposed recess having depth corresponding to the thickness of the flange, and with slots extending entirely through the flange and from its periphery tangentially to the central recess, and means delivering fuel under pressure to said slots.

2. In a fuel burning device, the combination of a chambered body having an outwardly projecting conical end and a discharge vent at the apex of the cone, means comprising a flanged disc dividing the interior of the chambered body into two compartments, one cylindrical and the other conical, said dividing means provided, on the conical-compartment side thereof, with a centrally disposed recess corresponding in depth to the thickness of the flange, and with channels in the flanged portion extending from the peripheral wall of the cylindrical compartment and delivering tangentially to said central recess, a perforated cylinder within the cylindrical compartment having pressure engagement with the flanged disc, and means delivering fuel under pressure to said perforated cylinder.

3. In a fuel burning device, the combination of a formation having an air discharge opening, a chambered body having an outwardly projecting conical end extending through said opening and having a discharge vent at the apex of the cone, means comprising a flanged disc dividing the interior of the chambered body into two compartments, one cylindrical and the other conical, said dividing means provided, on the conical-compartment side thereof, with a centrally disposed recess corresponding in depth to the thickness of the flange, and with channels in the flanged portion extending from the peripheral wall of the cylindrical compartment and delivering tangentially to said central recess.

4. In a fuel burning device, the combina-

tion of a chambered body having a conical shaped end and a discharge vent at the apex of the cone, the outer wall of said cone having an annular fin projecting between 5 the apex and base thereof, means dividing the interior of the chambered body into two compartments, one cylindrical and the other conical, said dividing means provided, on the conical-compartment side thereof, with a centrally disposed recess, and with channels extending from the peripheral wall of the cylindrical compartment and delivering tangentially to said central recess, and means delivering fuel under 10 pressure to the cylindrical compartment.

5. In a fuel burning device, the combination of a chambered body having a conical shaped end and a discharge vent at the apex of the cone, means dividing the interior 15 of the chambered body into two compartments, one cylindrical and the other conical, said dividing means comprising a cylindrical body having a projecting circular flange of greater diameter than that of 20 the main body and fitting the surrounding wall of the cylindrical compartment, having its face toward the other compartment provided with a centrally disposed circular recess and channels extending entirely 25 through the flange from the periphery thereof and delivering tangentially to the circular recess, and an annular body covering said channels on one side and having 30 an opening registering with the circular recess and flaring toward the conical compartment, a straining device positioned within the cylindrical compartment and means delivering fuel under pressure to the 35 straining device.

6. In a fuel burning device, the combination of a chambered body having a conical shaped end and a discharge vent at the apex of the cone, means dividing the interior 40 of the chambered body into two compartments, one cylindrical and the other conical, said dividing means provided, on the conical-compartment side thereof, with a centrally disposed recess corresponding in depth to the thickness of the disc, and with channels in the flanged portion extending from the peripheral wall of the cylindrical compartment and delivering tangentially 45 to said central recess, a perforated cylinder positioned within the cylindrical compartment, a fuel conductor delivering thereto, said conductor threaded into the chambered body and exerting pressure upon the perforated cylinder and the flanged disc.

7. In a fuel burning device, the combination of a chambered body having an outwardly projecting conical end and a discharge vent at the apex of the cone, means comprising a flanged disc dividing the interior of the chambered body into two compartments, one cylindrical and the other conical, said dividing means provided, on the conical-compartment side thereof, with a centrally disposed recess corresponding in depth to the thickness of the disc, and with channels in the flanged portion extending from the peripheral wall of the cylindrical compartment and delivering tangentially 50 to said central recess, a perforated cylinder positioned within the cylindrical compartment, a fuel conductor delivering thereto, said conductor threaded into the chambered body and exerting pressure upon the perforated cylinder and the flanged disc.

JOHN A. WILLNERS.
